UNITED STATES PATENT OFFICE.

DANIEL FORBES EBBERT, OF WHEELING, WEST VIRGINIA.

SHIPPING CASE.

Application filed December 28, 1921. Serial No. 525,301.

To all whom it may concern:

Be it known that I, DANIEL FORBES EBBERT, a citizen of the United States, and a resident of Wheeling, in the county of Ohio 5 and State of West Virginia, have invented a new and Improved Shipping Case, of which the following is a full, clear, and exact description.

This invention relates to improvements in 10 shipping cases, particularly to a metal shipping case which is designed for shipping dry goods and piece goods of various kinds.

The primary object of the invention is to do away with the very impractical wooden 15 cases or bales, which are now in use. The bales are objectionable for the reason that they are very often handled with hooks in transit and are neither fireproof nor water-proof. The bales also do not prevent chafing 20 of piece goods. Wooden cases are objectionable for the reason that they do not protect the goods in any manner from fire or water; they are very bulky and result in the payment of heavy freight rates on ship- 25 ments of piece goods.

An object of my invention, therefore, is to provide a metal shipping case which will effectively protect the goods shipped therein from fire and water as well as from chafing 30 in transit, which will not be nearly as bulky as the wooden cases now in use, and which for this reason will be useful not only in shipping, but in storing goods, and a case which will be comparatively light in weight, 35 simple and practical in construction, durable in use, and inexpensive to manufacture.

In addition to the advantages above enumerated, the metal cases will efficiently protect goods from soiling. It might also be 40 noted that since the container is less bulky than the ordinary wooden container, it will be possible to store a great many more packages either in a freight warehouse or in a freight car. When shipping goods by 45 freight, the metal container not only serves as a better protection for the goods in case of a freight wreck, but also effectively protects the goods from damage by water when shipped in the antiquated freight cars having 50 leaky roofs which are commonly employed. In considering the protection which the container affords the goods from water, it should also be noted that goods are often damaged by a defective sprinkler system in 55 warehouses. My container obviates this danger. When used for storage purposes,

the container is highly desirable because it may be very quickly opened and closed and will also serve to protect such goods as are affected by sun and light when exposed. 60

With these and other objects in view, the invention consists in certain novel features of construction and combination and arrangements of parts as will be more fully herein-after described and pointed out in the claims. 65

In the accompanying drawings:

Figure 1 is a perspective view of my improved shipping case;

Figure 2 is a view in section on the line 2-2 of Figure 3;

Figure 3 is an enlarged fragmentary view in side elevation showing the manner of locking the top and bottom on the case; and

Figure 4 is an enlarged sectional view on the line 4-4 of Figure 1.

Referring in detail to the drawings, it will be seen that my improved shipping case, which is formed of any metal suitable for the purpose, includes the usual rectangular body portion 1, and a removable cover and bottom, designated by the reference numerals 2 and 3 respectively. The invention in this case is believed to reside principally in the manner of locking the box cover and bottom upon the case. 85

It will be noted that the cover 2 which is preferably pressed from a single sheet of metal includes depending and defining flanges 4, which receive the upper end of the body 1. Referring particularly to Figures 2 and 3, it will be seen that at each side of the box adjacent the corners thereof, the flanges 4 are slotted, as indicated at 5, to provide bendable tongues 6, these tongues being slightly offset from the vertical plane 90 of the flanges and adapted to bend downwardly, the tongues being connected at their upper ends to the flanges. In like manner the body of the box adjacent its upper end is slotted at 7, to provide bendable tongues 100 8, the tongues 8 being connected at their lower ends to the box body and adapted to be bent outwardly through the slits 5, and then bent downwardly, as seen most clearly in Figures 2 and 3 to positively hold the box 105 cover against upward movement. Perforations 9 in the tongues 6 and 8 may receive a flexible device and seal (not shown) so that the consignee of a shipping case can readily tell whether or not the same has 110 been tampered with. The box bottom 3 which includes an upwardly presented

flange 10 similar to the flange 4 is likewise slotted to provide bendable tongues 11. Bendable tongues 12 integral with the box body are movable under the tongues 11 and 5 adapted to be bent upwardly, as seen in Figure 1, to securely lock the bottom of the box against movement, these tongues functioning in the same manner as the tongues 8.

For the purpose of strengthening the box 10 construction, the body may be formed either from a single sheet of material or from four sheets of material seamed together at the corners, as indicated at 13. Any type of metal seaming may be used which will add 15 to the strength and rigidity of the box, Figure 4 of these drawings illustrating one manner of seaming the corners.

Although I have illustrated one of the preferred embodiments of the invention, it 20 will be apparent that various slight changes and alterations might be made in the general form and arrangement of the parts described without departing from the invention, and hence I do not wish to limit myself to the precise details set forth, but shall 25 consider myself at liberty to make such slight changes and alterations as fairly fall within the spirit and scope of the appended claims.

30 I claim:

1. As a new article of manufacture, a metal shipping case comprising a body and a flanged closure for the same, the body and the flange of the closure being provided with 35 struck up tongues, the tongues of one overlying the spaces from which they are struck up and the tongues of the other being passed through said spaces and bent approximately parallel with the part from which they are 40 struck up.

2. As a new article of manufacture, a metal shipping case including a body having outwardly bendable struck-up tongues, and a removable cover having a depending defining flange integral with the cover, said flange 45 being slotted to provide outwardly bendable tongues connected at their upper ends to the flange and overlying the space between the slits, said bendable tongues of the body being passed through said slits under the 50 tongues of the flange and bent downwardly to hold the cover on the body.

3. As a new article of manufacture, a metal shipping case including a body having outwardly bendable struck up tongues, and a 55 removable cover having a depending defining flange integral with the cover, said flange being slotted to provide tongues connected at their upper ends to the flange, said tongues being offset and overlying the space 60 between the slits, said bendable tongues of the body being passed through said slits under the first mentioned tongues and bent downwardly to hold the cover on the body, the tongues on the body and cover having 65 openings therein adapted to receive a flexible device.

4. As a new article of manufacture, a metal shipping case comprising a rectangular body and removable flanged cover and bottom for 70 the body, the body and the flanges of the cover and bottom being provided with struck up tongues, the tongues of the said flanges being offset and overlying the spaces from which they are struck up and the tongues of 75 the body extending through the said spaces and bent approximately parallel with the body.

DANIEL FORBES EBBERT.
